TYPEWRITING MACHINE HAVING SELECTIVE CIRCUIT CLOSING MEANS, INCLUDING A CONDUCTIVE POWER ROLLER

Edward J. Rabenda, Poughkeepsie, N. Y., assignor to International Business Machines Corporation, New York, N. Y., a corporation of New York

Application December 29, 1950, Serial No. 203,378

17 Claims. (Cl. 197—5)

1

This invention relates to typewriting machines. An object of the present invention is to provide an improved selective circuit closing means suitable for use in typewriting machines to enable such machines to remotely control other apparatus.

An object is to provide a circuit closing means which requires only a very small amount of additional space in the typewriting machine thereby enabling the machine to be made more compact or allowing for the installation of auxiliary mechanism or apparatus without increasing the size of the machine.

An object is to provide a selective circuit closing means which does not impose any appreciable additional loads on the mechanisms of the machine over their normal loads.

An object is to provide a circuit closing means which takes advantage of already existing parts in the machine as a means of selectively closing circuits to thereby eliminate the necessity for providing a large number of additional parts for the purpose of exercising the circuit closing function.

An object is to provide a simple and effective selective circuit closing means which is especially useful in power operated typewriters to enable, for instance, the control by such a typewriter of an auxiliary machine such as a tape punch or card punch.

An object is to provide a selective contact means which requires very few additional parts over the normal number of parts incidental to the type bar operating mechanism of a power operated typewriter.

An object is to provide a selective contact means in which a very high contact pressure can be obtained without imposing any additional load on the power mechanisms of the typewriter.

Another object is to provide a selective contact means for power operated typewriters which makes use of the normal parts of the power mechanism to close the selective circuits rather than auxiliary parts operated thereby so as to insure that the circuits actually will be closed when the type bars are operated and not remain dependent upon additional parts which may break, get out of timing, or not operate at all.

Other objects of the invention will be pointed out in the following description and claims and illustrated in the accompanying drawings, which disclose, by way of example, the principle of the invention and the best mode, which has been contemplated, of applying that principle.

In the drawings:

2

Fig. 1 is a vertical section showing the invention as applied to a power operated typewriter.

Fig. 2 is a detail view in profile of one of the operating cams.

Fig. 3 is a bottom plan view of the cam shown in Fig. 2.

Fig. 4 is similar to Fig. 2 and shows a modified form of the cam which enables the contact mechanism for a single key to initiate a succession of impulses.

Fig. 5 is a diagram showing how the contact plates of the cams may be wired to control auxiliary apparatus in accordance with a conventional 2-hole combinational code.

The invention is disclosed in the drawings as applied to a well known form of electrically driven power-operated typewriting machine known commercially as the "IBM Electric," the power mechanism of which is disclosed in Patent No. 2,506,444. It will be understood, however, that the invention is not limited to embodiment in a typewriter of the form illustrated but may be embodied in other typewriters by suitable modifications of the power operating devices for the type bars and other instrumentalities of the typewriting machine.

Since the power mechanism is now well known in the art only a very brief description thereof will be given. The type bars, illustrated by the

single type bar 10 in Fig. 1, are actuated by electric motive power under control of character keys 11, which are pivoted on a cross rod 12 and restored by means of the springs 13. The power means includes, for each separate type bar 10 and its character key 11, a power unit having a sub-lever 14 pivoted at 15a on an adjustable fulcrum member 15 which is suitably mounted in a frame 15b. The sub-levers 14 are retained in pivotal engagement with the fulcrum members 15 by

means of springs 16 which urge the sub-levers 14 in a counterclockwise direction so as to tend to restore the type bars 10. Links 17 connect sub-levers 14 to type bars 10. The latter are pivotally mounted in a well known way on a curved fulcrum wire 18 in the usual segment.

Pivoted at 14a on the sub-levers 14 are the operating cams 19 which, in the present case, are modified to enable them to function as circuit closing devices. The sub-levers 14 are provided with interposers 20 which are pivotally slidably mounted at 14b on extensions of the sublevers 14 and are urged to the left by means of the springs 21 which are anchored to lugs formed in the sub-levers 14 and to lugs at the right-hand ends of the interposers 20. The springs 21 hold

the interposers 20 in their left-hand positions with bent-over lugs 20a thereof directly underneath lugs 11a formed in the keys 11.

The cams 19 are urged in a counterclockwise direction by springs 22 to engage extensions thereof with bent-over lugs 20b formed in the interposers 20.

When any key 11 is depressed, the interposer 20 therefor is depressed and thereby the corresponding cam 19 is urged clockwise until the tread of the cam engages the power roller PR which rotates in the direction of the arrow (Fig. 1). The tread is eccentric with respect to pivot 14a, consequently the rotation of the cam will urge the pivot 14a of the cam to the right and rock the sub-lever in a clockwise direction to actuate the related type bar to the printing position. Subsequently, the extension 19a of the cam will strike an adjustable finger 23 and, by sliding along said finger, effect the positive disengagement of the cam 19 from the power roller PR.

The foregoing mechanism is well known in the art and fully described in the above patent in greater detail.

For the purpose of effecting selective closure of circuits which are representative of the type bars and other instrumentalities which are operated, the power roller PR is provided with a sleeve of so-called conductive rubber instead of the usual rubber sleeve and the cams 19, instead of being molded of a single piece of plastic, or made of a single piece of metal, are arranged to provide two contact shoes which will be electrically connected by the conductive rubber sleeve when the cam is engaged with the power roller PR.

The construction of a cam 19 is shown in Figs. 2 and 3 in which the body of the cam is made of an insulating material such as molded nylon, to the sides of which are secured in any suitable way the electrically conductive contact plates 19b. These contact plates are insulated from each other by the body of the cam and the left-hand edges thereof are shaped to form with the body 19 a continuous tread surface which is designed to roll over the surface of the power roller PR when the cam is engaged therewith, as described above.

When operated in this fashion, the conductive rubber will establish an electrical connection between the contact plates 19b and it only remains to provide a means of connecting the plates 19b to external control circuits which means naturally must remain effective while the cam 19 is in motion during the operating cycle of the type bar. This means may conveniently take the form of very weak metallic springs or equivalent flexible or resilient electrically conductive members 24 which are hooked into holes 19c in the plates. The body of the cam 19 is cut away as shown in Fig. 3 adjacent the holes 19c to form an insulating barrier 19d which prevents the springs 24 from making contact with each other at the points where they are anchored to the plates 19b.

The springs 24 are anchored to suitable terminals carried by a cross bar 25 which may be of insulating material or the terminals themselves may be insulated from the cross bar 25 which may then be made of metal. The pair of springs 24 associated with each cam provide a means of conducting current from external circuits to the plates 19b.

In order to function as a circuit closing device,

it is necessary that only one plate 19b be provided for each cam 19. However, the wear on the tread surface of the cam will be more evenly distributed if the cams are provided with two plates with the insulating material sandwiched between as disclosed in Figs. 2 and 3. In the present case, the fact that two plates are provided is of convenience in using the invention in conjunction with a specific type of apparatus which is operated or controlled in accordance with a 2-position combinational code.

In order to conduct current in the power roller PR, there is provided a common brush CB (Fig. 1) which may bear on the surface of the rubber or on a metallic band associated with the power roller and electrically connected with the conductive sleeve.

In Fig. 5, there is shown how the electric connections are made to the power roller and the conducting plates 19b to enable the typewriter to control an auxiliary machine such as, for example, a machine for punching accounting and statistical record cards in accordance with the well known twelve position 2-hole alphabetical combinational code. A machine of this type is disclosed in Patent No. 1,976,618.

The alphabet in accounting and statistical record cards is represented by combinations of holes in the "0," "11," and "12" index-point positions, respectively, with holes in the "1" to "9" index-point positions. Thus, the letter "A" is represented by the combination of a "12" hole and a "1" hole punched in a single column of the card. The wires W0 to W12 in Fig. 5 may be connected to the twelve punch selecting magnets of a punch such as disclosed in the above patent so that the common brush CB, power roller PR, and the conductive plates 19b function to control the punch magnets in the above patent in the same way as the card sensing brushes do. For example, when the A key of the typewriter is depressed, the conductive plates 19b for the A key will close a circuit from the power roller PR to the wire W12 and also to the wire W1 so that current can flow from the wire W13 through the power roller PR, the A conductive plates 19b to the wires W12 and W1 and thence to the "12" punch magnet and the "1" punch magnet which will result in punching the combination of a "12" hole and a "1" hole in the particular column of the card which is in register with the punch, in the same general fashion as a "12" brush and a "1" brush in the above patent close circuits to the punch magnets.

The conductive plates 19b for the numerical keys of the typewriter close only one circuit to the corresponding wires W0 to W9. Thus, if the digit "1" is printed, the operative conductive plate 19b corresponding to the "1" key will close a circuit to the wire W1 and thus cause the "1" punch magnet to operate.

It will be understood that by applying solenoids to the keys 11 of a second typewriter, it will be possible for the first typewriter to control the second typewriter by direct circuits from the conductive plates 19b of the first machine to the solenoids operating the corresponding keys of the second typewriter.

The foregoing are merely illustrative ways in which the machine may be used in accordance with well-known needs. It will be understood that the cams 19 may be provided with more than two conductive plates 19b, if necessary, to enable each cam to close several separate circuits or the cam may be made wholly of metal

or with a metallic insert forming the entire tread so as to close a single circuit.

The principal advantage of the foregoing selective circuit closing means is that it requires very few additional parts which is a distinct advantage in a mechanism of this type because of the fact that typewriting machines are usually internally crowded with the essential parts of the typewriter mechanisms and it is seldom very convenient, when the power mechanism is designed for maximum efficiency, convenience, durability, and minimum cost, to apply auxiliary contacts without considerable additional mechanism. In the past, it has been found that the installation of this additional mechanism not only has been very inconvenient and often made it necessary to enlarge the base of the machine, but the additional mechanism has imposed an additional load on the power mechanism, thereby adversely affecting its operation.

In the present case, the springs 24 are the only additional parts which must be supplied to the type bar operating mechanisms to render the circuit closing means effective and these springs are so arranged that they are normally initially under a relatively slight tension which is relaxed during the cycles of operation of the type bars and the retensioning of these springs when the type bars restore is very slight so as to impose no additional burden on the restoring springs 16 and 22 which are greatly superior in strength to the springs 24. Furthermore, the springs 24 are disposed in such a relationship to the cams 19 that the effect thereof on the cams 19 is so trifling as to have no effect on the force of the blow of the type bars.

An advantage of the mechanism is that good electrical contact is assured since the pressure between the conductive plates 19b and the power roller PR naturally is quite heavy in view of the fact that the power roller PR operates the power units 14 against the inertia of the parts comprising the power units and the type bars and against the tension of the springs 16 so that there should be no slippage of the treads of the cams 19 on the power roller PR. If such a slippage does occur, it will tend toward the establishment of even better contact due to the wiping action which by itself would be a distinct advantage, if it occurred.

It will thus be seen that not only is the contact closing means very positive and reliable in its action, but the cost of installing it in the machine is negligible in comparison with other arrangements where the machine is provided with a fixed bank of contacts with specially constructed cams having extension arms, insulating pins, and the like for operating the contacts. In such structures, the contact pressure necessarily must be kept as low as possible, otherwise the type bar mechanisms are likely to be excessively loaded and a disadvantage of such mechanisms is that it is very difficult to adjust the spring tension of all of the contact springs so that all of the power units are equally loaded. In the present case, there is no such problem as there is nothing at all to adjust and the only vital reaction exerted on the power unit is the normal reaction between the power actuator and the power unit which is incidental to the operation of the type bar by power in any case.

In the drawings, the contact elements 19b are shown as being coextensive with the full length of the tread surface of the cam 19 on the assumption that it is desirable to maintain full

contact throughout the entire period in which the cam 19 is in contact with the power roller PR. It is possible to obtain relative timing between the plates 19b or cause these plates to individually close more than one circuit per operation of the type bar. For example, the edges of the plates 19b along the tread could be cut away in such fashion that the actual closing of the circuit is delayed or shortened, as desired. By cutting a shallow notch in the tread portion of the plates 19b of suitable length, as in Fig. 4, each plate may be caused to emit two electrical pulses or more according to the number of notches cut in the plate. Thus, the mechanism is suitable for communication systems in which each key must control the transmission of a series of impulses rather than a single impulse. Various other modifications of the plates 19b will occur to those skilled in the art to adapt the circuit closing means to the needs of control business machines or printing telegraph receivers.

While there have been shown and described and pointed out the fundamental novel features of the invention as applied to a preferred embodiment, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. In a power operated typewriter, character keys, type bars, a continuously movable main power actuator having an electrically conductive power driving surface and a series of power units having driven elements selectively coupled by said keys with said actuator for operating the type bars selectively, said elements having electrically conductive portions making electrical contact with said driving surface while the type bars are being operated by said actuator.
2. A power mechanism for typewriters and like machines comprising a continuously movable main power actuator having a surface of electrically conductive material; normally inactive power units, each for operating a different instrumentality of the typewriter and including a normally disengaged driven element having an electrically conductive portion engageable with said surface so as to close a circuit when the driven element is engaged with said actuator; and means to selectively engage said elements with said actuator.
3. In a machine of the class described, a continuously movable main power actuator having an electrically conductive driving surface, a power unit having an element engageable with said surface to enable said power unit to be operated by said actuator, one of said surface and said element being insulatably mounted so as to enable a circuit to be closed by contact therebetween only when said element is engaged with said actuator, and means to effect driving engagement between said actuator and said element.
4. In a typewriting machine, a printing device, a key representative of said device, a main power roller having a driving surface of electrically conductive material, and a power unit having a mechanical connection to said printing device and including a cam element engageable by said key with said power roller to actuate said printing device and making electrical connection with said

surface only when the power roller is actuating said power unit.

5. A power mechanism for typewriting and like machines comprising a continuously movable main power actuator having an electrically conductive surface, a power unit having a biased inoperative position in which it is free of said actuator and an operative position in which it engages with said actuator and including an element having an electrical contact surface engaging said conductive surface when the power unit is engaged with said actuator, and means to engage said power unit with said actuator.

6. A power mechanism for typewriters and like machines comprising a continuously movable main power actuator having an electrically conductive surface, a power unit having a biased inoperative position in which it is free of said actuator and an operative position in which it engages with said actuator for operation by the latter and including an element which is normally electrically insulated from said surface but arranged to make electrical contact with said surface to close an external circuit when said power unit is engaged with said actuator, and means to cause said power unit to engage said actuator.

7. In a machine of the class described, a power roller having an electrically conductive driving surface, a power unit comprising a sub-lever mounted for rocking movement and a cam initially rotatable on said lever to engage the cam with said surface for subsequent driving by said roller, said cam having an electrically conductive portion making electrical contact with said surface when said cam is driven by said roller, and means to initially cause rotation of said cam.

8. In combination, a power roller having an electrically conductive surface, a normally idle power unit having a cam rotatable by said power roller and having electrical contact means making at least one electrical contact with said power roller surface when rotated by the latter, and means to move the cam into rotatable engagement with the power roller.

9. In combination with a rotary power actuator having an electrically conductive driving surface, a power unit having an element initially movable into engagement with said actuator for rotation thereby and including electrical contact means operative to close a plurality of separate circuits by rolling contact with said rotary actuator, and means to engage said element with said actuator.

10. In combination, a continuously movable power actuator having an electrically conductive surface, a normally idle actuated device including an element engageable with said actuator to enable the latter to actuate said device and including contact means arranged to make at least one electrical contact with said surface during the period of operation of said device by said actuator.

11. In a power operated typewriter, character keys, type bars, a main power actuator having an electrically conductive power driving surface and a series of power units having driven elements selectively coupled by said keys with said actuator for operating the type bars selectively, said elements having electrically conductive portions making rolling electrical contact with said driving surface while the type bars are being operated by said actuator.

12. In a power operated typewriter, character keys, type bars, a main power actuator having an electrically conductive power driving surface and a series of power units having driven elements selectively coupled by said keys with said actuator for operating the type bars selectively, said elements having electrically conductive portions making a plurality of successive electrical contacts with said driving surface while the type bars are being operated by said actuator.

13. A power mechanism for typewriting and like machines comprising a main power actuator having an electrically conductive surface, a normally idle power unit engageable with said actuator and including an element having a contact element progressively engaging different successive portions of said conductive surface when the power unit is engaged with said actuator, and means to engage said power unit with said actuator.

14. A power mechanism for typewriters and like machines comprising a main power actuator having an electrically conductive surface, a normally idle power unit engageable with said actuator for operation by the latter and including an element which is normally electrically insulated from said surface but arranged to make rolling electrical contact with said surface to close an external circuit when said power unit is engaged with said actuator, and means to cause said power unit to engage said actuator.

15. In combination, a power roller having an electrically conductive surface, a normally idle power unit having a cam rotatable by said power roller and having electrical contact means making at least one rolling electrical contact with said power roller when rotated by the latter, and means to move the cam into rotatable engagement with the power roller.

16. In combination, a rotary actuator having an electrically conductive driving surface, a normally idle coupling element adapted for rotary driven engagement with said actuator and having a contact element electrically contacting said driving surface for rotation thereby when the first element is engaged with the actuator, and means to engage said coupling element with said actuator.

17. In a power actuated mechanism having an initiating means and a corresponding part to be actuated, a continuously movable power actuator having an electrically conductive driving surface, and a power unit operatively connected to move said corresponding part independently of said initiating means and having an element movable into contact with said driving surface by said initiating means to actuate said part, said element having an electrically conductive portion engageable with said surface to close a circuit when the element is engaged with said actuator.
